UNITED STATES PATENT OFFICE.

FREDERICK P. PALEN AND WILLIAM BURLINGHAM, OF NEWPORT NEWS, VIRGINIA.

WATER-TUBE BOILER.

1,152,341.

Specification of Letters Patent. Patented Aug. 31, 1915.

Application filed October 18, 1914. Serial No. 866,425.

To all whom it may concern:

Be it known that we, FREDERICK P. PALEN and WILLIAM BURLINGHAM, citizens of the United States, residing at Newport News, in the county of Warwick, State of Virginia, have invented a new and useful Water-Tube Boiler, of which the following is a specification.

Our present invention relates to a novel construction of a water tube boiler wherein is employed an upper or central steam drum which is connected on opposite sides with a series of drums, by means of nests of tubes, the central drum being of such size as to permit the removal of any of the tubes without disturbing the other tubes, and a plurality of baffles being provided, the result of which is that the products of combustion are consumed and the heat units are effectively utilized to raise the water in the boiler to the desired temperature and to obtain the requisite circulation between the steam drum and the series of water drums. It is essential in devices of this character not only that the proper combustion is effected but that the heat units be directed so as to impinge in a correct manner against the heating surfaces, to cause an effective and rapid circulation and rapid generation of steam under all conditions, and by the present novel collocation of steam drum, water drums, tubes and baffle plates, a complete combustion of the gases takes place prior to the passage of the products of combustion to the stack or exhaust flue, so that any oxygen admitted will combine with the products of combustion and a combustion takes place which is more perfect and thorough than has heretofore been accomplished.

We employ baffle plates on opposite sides of each nest of tubes. The lower of said baffle plates converge upwardly so that the hot gases are temporarily pocketed in the top of the combustion chamber below the steam drum, so that the surfaces of the lower nest of water tubes are acted on, not only by the first combustion which takes place in proximity to the grate, but also by the secondary combustion which takes place in the upper portion of the combustion chamber, which is accompanied by the resultant intense heat, and which concentrates in the upper part of the combustion chamber in proximity to the lower portion of the steam

drum and the lower nests of tubes connected therewith. By such construction, intense heat is applied to the inner or lower nests of water tubes and a rapid upward circulation is created, which is directed in a downward direction to the upper nests of tubes and thereby prevents any lodgment of scale or impurities in the water tubes. We are thus enabled to initially heat the lower nests of tubes to a high degree, which causes a rapid upward circulation, such heat being rapidly lost as the products of combustion pass around and beyond the upper diverging baffle plates, so that the circulation and steam generated in the boiler is greatly increased and a maximum utilization of the heat units is obtained. It will therefore be seen that our novel arrangement of drums, tubes and baffle plates causes the heat to be applied so a rapid circulation of water takes place in an up current in the tubes next to the furnace and a resulting down current in the tubes farthest away from the furnace. In order to assist this circulation and in order to heat the cold feed water introduced into the boiler in a manner that will not retard or interfere with the natural circulation of the water in the boilers, we have devised a novel method of introducing the feed water by introducing it at the upper end of the tubes in which the down circulation takes place so it will be heated while passing down through these tubes. This method also assists the down circulation in these tubes and thereby assists the general circulation of the water in the boiler.

With the above in view, our invention consists of a novel water tube boiler, which includes a novel construction and arrangement of a steam drum, water drums, connecting tubes, baffle plates and feed pipes.

Other novel features of our invention will hereinafter appear in the detailed description.

For the purpose of illustrating our invention, we have shown in the accompanying drawings forms thereof which are at present preferred by us, since the same will give in practice satisfactory and reliable results, although it is to be understood that the various instrumentalities of which our invention consists can be variously arranged and organized and that our invention is not limited

to the precise arrangement and organization of these instrumentalities as herein shown and described.

Figure 1 represents a side elevation of a water tube boiler embodying our invention. Fig. 2 represents a sectional elevation. Fig. 3 represents a side elevation, partly in section, of another type of water tube boiler embodying our invention. Fig. 4 represents a sectional elevation of Fig. 3. Fig. 5 represents a section through the boiler shell, tubes and feed pipe.

Similar numerals of reference indicate corresponding parts in the figures.

Referring to the drawings. Referring first to the embodiment seen in Figs. 1 and 2, 1 designates the boiler setting or brick-work within which is contained a grate 2. 3, 4 and 5 represent intercommunicating water drums supported on the boiler setting 1 and connected with the steam drum 9 by nests of tubes. 6, 7 and 8 designate similar intercommunicating water drums supported on the opposite side of the boiler setting and connected with the steam drum 9 by nests of tubes. We provide lower nests of tubes 10 and 11 connected with the lower water drums 5 and 8, respectively, intermediate the nests of tubes 12 and 13, which communicate with the intermediate water drums 4 and 7, respectively, and upper nests of tubes 14 and 15, which communicate with the upper water drums 3 and 6 respectively. 16 and 17 designate diverging baffle plates, which are supported in proximity to the steam drum 9 in any desired manner and which are directed downwardly and outwardly and preferably into close proximity to the lower nests of water tubes 10 and 11, respectively, it being noted that these baffle plates are shorter than the tubes in proximity to which they are placed and terminate at a point above the lower ends of said tubes. 18 and 19 designate upwardly converging baffle plates which are supported in proximity to the boiler setting and are directed toward the steam drum between the lower and intermediate nests of tubes, and terminate a desired distance from the steam drum. 20 and 21 designate baffle plates supported in proximity to the steam drum 9 and directed downwardly between the upper and intermediate nests of tubes, so as to overlie the upper portion of the intermediate nests of tubes and terminate a desired point above their lower ends. 22 and 23 designate upper baffle plates supported in proximity to the water drums 3 and 6, respectively, and overlying the upper nests of tubes 14 and 15, respectively, and terminating a desired distance from the steam drum 9. 24 and 25 designate water conveying pipes which connect the lower portion of the interior of the steam drum 9 with the water drums 5 and 8, respectively. The water drums 3 and 4 are in communication with each other through the conduits 26, and the water drums 4 and 5 are in communication with each other through the conduits 27. The water drums 6 and 7 are in communication through the conduits 28 and the water drums 7 and 8 are in communication through the conduits 29. 59 represents a section of the boiler shell and 60 the ends of the boiler tubes expanded in the boiler shell through which the down circulation takes place. 62 represents the main feed pipes which have branches 61 for introducing the feed water into the upper end of the tubes in which the down circulation takes place, whereby the natural or normal circulation is accelerated. By arranging the baffle plates in the manner set forth, the products of combustion, after being temporarily pocketed in the combustion chamber by the baffle plates 16 and 17, respectively, and after impinging on the bottom of the steam drum 9, pass around the lower nests of tubes between the baffle plates 16 and 18 and the baffle plates 17 and 19 and then are directed downwardly between the baffle plates 18 and 20 and the baffle plates 19 and 21, and are then directed upwardly between the baffle plates 20 and 22 and the baffle plates 21 and 23, passing through the flues 30 to the stack 31.

Referring now to the embodiment seen in Figs. 3 and 4, we have shown in this embodiment, water drums having a vertical arrangement and connected with their lower ends by means of nipples with horizontally arranged drums or chambers. 32 and 33 designate horizontal drums or chambers, the drum 32 being connected by nipples 34 with the vertically arranged water drums 35. The horizontally arranged drum 33 is connected by nipples 36 with the vertically arranged water drums 37. The horizontal drums 32 and 33 are supported on a steel or other foundation 38. 39 designates a grate. 40 designates the central or steam drum which is connected with the drums 35 and 37 by nests of tubes. 41 and 42 designate lower nests of tubes. 43 and 44 designate intermediate nests of tubes, and 45 and 46 designate upper nests of tubes. 47 designates a circulating pipe communicating with the drums 40 and drum 32, and 48 designates a similar circulating pipe which is connected with the steam drum 40 and the horizontal drum 33. 49 and 50 designate diverging baffle plates which are directed downwardly from the steam drum 40 and extend beneath or within the lower nests of tubes 41 and 42. 51 and 52 designate baffle plates located between the intermediate and lower nests of tubes and said baffle plates have one end located in proximity to their respective water drums 35 and 37 and then converge upwardly and terminate beneath

the steam drum 40. 53 and 54 designate a third set of baffle plates, the upper ends of which are in close proximity to the steam drum 40, and their lower ends terminate a desired distance from the water drums 35 and 37. These baffle plates 53 and 54 are located between the upper and intermediate nests of tubes. 55 and 56 designate a fourth or upper set of baffle plates, which extend from the water drums 35 and 37, respectively, toward the steam drum 40 and terminate a desired distance therefrom, said baffle plates being located above the upper nests of tubes. 62 represents the main feed pipes and 61 the branch pipes which introduce the feed water into the tubes in which the down circulation takes place. The products of combustion impinge against the bottom of the steam drum 40 and are then directed downwardly by the baffle plates 49 and 50, then pass around the lower nests of tubes 41 and 42, thence between the baffle plates 51 and 53 and the baffle plates 52 and 42 around the intermediate nests of tubes. The products of combustion then pass around the upper nests of tubes between the baffle plates 53 and 55 and between the baffle plates 54 and 56, and then pass to the exhaust flues 57 and 58, respectively.

30 In our device we provide a central steam drum of such diameter that it will permit of sufficient space to allow the tubes to be withdrawn entirely thereinto, so that they can be readily removed from the central steam drum through a single man-hole, thereby insuring the maximum strength and durability of the boiler without increasing the expense of the construction.

Owing to the provision of our novel arrangement of baffle plates, hot gases are temporarily retarded in the top of the combustion chamber and the passage of the gases around the nests of tubes is also retarded by the baffle plates in such a manner that substantially all of the heat units are utilized before the products of combustion pass through the discharge flues.

In accordance with our present invention, we have provided a series of intercommunicating water drums on each side of the main and central drum, it being understood that such water drums may be horizontally, vertically, or otherwise arranged, and the baffle plates are arranged in such a manner with respect to the nests of tubes that a thorough circulation and a maximum steam generation is obtained.

Our novel boiler carries several times the amount of water other types of water tube boilers are adapted to carry, and provides a water area for the disengagement of the steam from the surface of the water, several times as great as that of other types of water tube boilers. Furthermore, the large steam space makes it unnecessary to employ a

steam separator, since the water is not carried up into the steam, as is the case in water tube boilers of ordinary construction, which under a heavy fire are likely to prime and carry water over into the steam.

The feed pump can be run with but little attention from the operator, even under considerable variations in load. The water tube boiler, as herein disclosed, with the novel arrangement of baffling, presents no pockets for the deposition of foreign material, which is largely the cause of the burning out of the tubes, and sufficient space is left to permit the hot gases to pass to all points of the tubes, so that air admitted can combine with the carbon monoxide before it passes to the exhaust flue or stack.

It will now be apparent that we have devised a novel and useful construction of a water tube boiler which embodies the features of advantage enumerated as desirable in the statement of the invention and the above description, and while we have, in the present instance, shown and described preferred embodiments thereof which will give in practice satisfactory and reliable results, it is to be understood that the same are susceptible of modification in various particulars without departing from the spirit or scope of the invention or sacrificing any of its advantages.

Having thus described our invention, what we claim as new and desire to secure by Letters Patent, is:—

1. A water tube boiler, comprising an upper steam drum, lower water drums, nests of tubes connecting the steam and water drums, a set of baffle plates extending from the steam drum toward the water drums and located near the lower portion of the tube nests whereby an opening is provided between the ends of the baffle plates and the water drums for the admission of hot gases to the tube nests, a second superimposed set of baffle plates located in the tube nests and extending from the water drums toward the steam drum, a third superimposed set of baffle plates located in the tube nests and extending from the steam drum toward said water drums, and a fourth set of superimposed baffle plates located at the upper portion of the tube nests and extending from the water drums toward the steam drums, and said superimposed sets of baffle plates forming openings to cause a circuitous travel of the hot gases around the nests of tubes.

2. A water tube boiler, comprising an upper steam drum, lower water drums, nests of tubes connecting the steam and water drums, the steam drum being of a size to permit removal of a tube without disturbing other tubes, a set of baffle plates extending from the steam drum toward the water drums and located near the lower portion of the tube nests whereby an opening is pro-

vided between the ends of the baffle plates and the water drums for the admission of hot gases to the tube nests, a second superimposed set of baffle plates located in the tube nests and extending from the water drums toward the steam drum, a third superimposed set of baffle plates located in the tube nests and extending from the steam drum toward said water drums, and a fourth set of superimposed baffle plates located at the upper portion of the tube nests and extending from the water drums toward the steam drums, and said superimposed sets of baffle plates forming openings to cause a circuitous travel of the hot gases around the nests of tubes.

3. A water tube boiler, comprising an upper steam drum, a plurality of intercommunicating lower water drums on opposite sides of said steam drum, nests of tubes connecting the steam and water drums, a set of baffle plates extending from the steam drum toward the water drums and located near the lower portion of the tube nests whereby an opening is provided between the ends of the baffle plates and the water drums for the admission of hot gases to the tube nests, a second superimposed set of baffle plates located in the tube nests and extending from the water drums toward the steam drum, a third superimposed set of baffle plates located in the tube nests and extending from the steam drum toward said water drums, and a fourth set of superimposed baffle plates located at the upper portion of the tube nests and extending from the water drums toward the steam drums, and said superimposed sets of baffle plates forming openings to cause a circuitous travel of the hot gases around the nests of tubes.

4. A water tube boiler, comprising an upper steam drum, lower water drums at opposite sides of the steam drum, the water drums at a side communicating with each other through restricted water passages, nests of tubes connecting the steam and water drums, a set of baffle plates extending from the steam drum toward the water drums and located near the lower portion of the tube nests whereby an opening is provided between the ends of the baffle plates and the water drums for the admission of hot gases to the tube nests, a second superimposed set of baffle plates located in the tube nests and extending from the water drums toward the steam drum, a third superimposed set of baffle plates located in the tube nests and extending from the steam drum toward said water drums, and a fourth set of superimposed baffle plates located at the upper portion of the tube nests and extending from the water drums toward the steam drums, and said superimposed sets of baffle plates forming openings to cause a circuitous travel of the hot gases around the nests of tubes.

circuitous travel of the hot gases around the nests of tubes.

5. A water tube boiler, comprising an upper steam drum, lower water drums, nests of tubes connecting the steam and water drums, a set of baffle plates extending from the steam drum toward the water drums and located near the lower portion of the tube nests whereby an opening is provided between the ends of the baffle plates and the water drums for the admission of hot gases to the tube nests, a second superimposed set of baffle plates located in the tube nests and extending from the water drums toward the steam drum, a third superimposed set of baffle plates located in the tube nests and extending from the steam drum toward said water drums, and a fourth set of superimposed baffle plates located at the upper portion of the tube nests and extending from the water drums toward the steam drums, and said superimposed sets of baffle plates forming openings to cause a circuitous travel of the hot gases around the nests of tubes.

6. A water tube boiler, comprising an upper steam drum, vertically extending lower water drums, nests of tubes connecting the steam and water drums, a set of baffle plates extending from the steam drum toward the water drums and located near the lower portion of the tube nests whereby an opening is provided between the ends of the baffle plates and the water drums for the admission of hot gases to the tube nests, a second superimposed set of baffle plates located in the tube nests and extending from the water drums toward the steam drum, a third superimposed set of baffle plates located in the tube nests and extending from the steam drum toward said water drums, and a fourth set of superimposed baffle plates located at the upper portion of the tube nests and extending from the water drums toward the steam drums, and said superimposed sets of baffle plates forming openings to cause a circuitous travel of the hot gases around the nests of tubes.

7. A water tube boiler, comprising an upper steam drum of relatively large diameter, a plurality of side water drums, three series of water tubes on each side of said steam drum, common to said steam drum and said water drums, a lower pair of baffle plates, diverging downwardly from said steam drum, a second pair of superimposed baffle plates, above said lower baffle plates, and converging upwardly from said water drums, a third pair of superimposed baffle plates diverging downwardly from said steam drum, and a fourth uppermost superimposed pair of baffle plates converging upwardly toward said steam drum from said water drums, said superimposed sets of baffle

plates forming openings to cause a circuitous travel of the hot gases, around said water tubes.

8. A water tube boiler, comprising an upper steam drum of relatively large diameter, a plurality of side water drums, three series of water tubes on each side of said steam drum, common to said steam drum and said water drums, a lower pair of baffle plates, 10 diverging downwardly from said steam drum, a second pair of superimposed baffle plates, above said lower baffle plates, and converging upwardly from said water drums, a third pair of superimposed baffle 15 plates diverging downwardly from said steam drum, and a fourth uppermost superimposed pair of baffle plates converging upwardly toward said steam drum from said water drums, said superimposed sets of baffle 20 plates forming openings to cause a circuitous travel of the hot gases, around said water tubes, in combination with a pair of main feed water pipes located at opposite sides of said steam drum and provided with branch pipes for discharging the feed water into the upper ends of the tubes in which the downward circulation takes place, 25 thereby accelerating said circulation.

10. A water tube boiler consisting of an upper steam drum, lower water drums and nests of tubes connecting the steam and water drums, in combination with feed pipes 55 arranged so as to introduce the feed water into the upper end of the tubes in which the down circulation takes place.
11. In a water tube boiler, an upper steam drum, lower water drums and nests 60 of tubes connecting the steam and water drums, in combination with feed pipes, and branch pipes for introducing the feed water into the top of the boiler tubes.
9. A water tube boiler, comprising an upper steam drum of relatively large diameter, a plurality of side water drums, three series 30 of water tubes on each side of said steam drum, common to said steam drum and said water drums, a lower pair of baffle plates, diverging downwardly from said steam drum, a second pair of superimposed baffle 35 plates, above said lower baffle plates, and

converging upwardly from said water drums, a third pair of superimposed baffle plates diverging downwardly from said steam drum, and a fourth uppermost superimposed pair of baffle plates converging upwardly toward said steam drum from said water drums, said superimposed sets of baffle plates forming openings to cause a circuitous travel of the hot gases, around said water tubes, in combination with a pair of 40 main feed water pipes located at opposite sides of said steam drum and provided with branch pipes for discharging the feed water into the upper ends of the tubes in which the downward circulation takes place, 45 thereby accelerating said circulation.

10. A water tube boiler consisting of an upper steam drum, lower water drums and nests of tubes connecting the steam and water drums, in combination with feed pipes 55 arranged so as to introduce the feed water into the upper end of the tubes in which the down circulation takes place.

11. In a water tube boiler, an upper steam drum, lower water drums and nests 60 of tubes connecting the steam and water drums, in combination with feed pipes, and branch pipes for introducing the feed water into the top of the boiler tubes.
